UNITED STATES PATENT OFFICE.

ANDREW V. CLELAND, OF MINNEAPOLIS, MINNESOTA.

GRAIN-TESTING MACHINE.

Application filed August 8, 1925. Serial No. 49,109.

The object of my invention is to provide a simple inexpensive apparatus by means of which the seeds, wild oats and refuse material mixed with a sample of wheat can be 5 easily and quickly removed to enable the operator to accurately determine the grades of the wheat from samples taken at random in a car. These samples are collected when the cars of grain arrive at a terminal point 10 and the proper grade of the grain or the dockage is determined by ascertaining as near as possible the percentage of seeds and refuse material to the grains of wheat in each sample. Evidently, the accuracy of the test 15 or the grading determines the value of the carload of grain to the farmer or shipper and it is extremely important that the proper percentage of the waste material to the wheat be accurately determined when the 20 grade is established.

A further object is to provide an apparatus of the class described which will be comparatively compact in construction, easily operated and require but a small space for 25 operation and storage.

The invention consists generally in various constructions and combinations all as herein-after described and particularly pointed out in the claims.

30 In the accompanying drawings forming part of this specification,

Figure 1 is a side elevation of a dockage grain tester embodying my invention;

Figure 2 is a longitudinal sectional view 35 of the same;

Figure 3 is an end view;

Figure 4 is a sectional view on the line 4-4 of Figure 2;

Figure 5 is a detail sectional view showing the arrangement of the pockets in the 40 rotating drum; and

Figure 6 is a perspective view of one of the sections or staves of the rotating drum.

In the drawings, 2 represents a suitable 45 base. Mounted thereon at one end is a bracket 3, supporting a hopper 4 wherein the sample of grain mixed with the seeds and other refuse material is deposited. The bottom of this hopper is a trough 5 having a feed auger 6 and a gear 7. A shaft 9 is mounted in bearings on the bracket 3 and has a gear 10 meshing with the gear 7 and a crank 11 by means of which the shaft 9 may be revolved and with it the gears 7 and 50 10 and the feed auger 6. The shaft 9 projects into a rotating member that is octagonal

preferably in cross section composed of sections A and B placed end to end with the abutting ends within a band or ring 12 and secured thereto by suitable means such as 60 screws 13. Each cylinder is composed of a series of bars or staves 14 and 14^a made in any suitable manner, but preferably of cast material, the staves 14 having a series of webs or ribs 15 thereon transversely arranged in 65 such relation to each other that when the staves are assembled in an octagonal form, the ribs will form a continuous spiral web leading from end to end of the members. Between these webs, a continuous spiral passage 16 is provided and the bottom of this 70 passage in the staves 14 is provided with a series of pockets 17 of such size that they will collect the fine seeds such as wild mustard and seeds of similar size and shape 75 delivered to the interior of the rotating member by the operation of the feed or spiral 6. A hub 18 is secured on the inner end of the shaft 9 and has spokes 19 radiating out to the bars or staves within the band 12 and 80 through the shaft 9 and the spokes 19 a rotary movement is imparted to the device when the shaft 9 is revolved. The trough projects into the separating device to deliver the material from the auger at the receiving 85 end of the spiral. The pockets in the bottom of the spiral from the receiving end to the middle of the rotating member are preferably of substantially the same size and are adapted to receive round seeds such as wild mustard 90 and the like, and in the rotation of the member, these seeds are carried up on one side and when they reach a predetermined point they will be discharged by gravity from the pockets. On the up side of the rotating 95 member, I provide a pan 20 mounted upon an arm 21 that is adjustable on an upright standard 22 by means of slots 23 and bolts 24. By this means, the pan may be raised or lowered until the desired elevation is 100 obtained. As indicated in Figure 2, it is positioned near the up side of the rotating member so that the seeds as they fall from the pockets in the member will drop into the pan. Any suitable means may be provided for binding the staves or bars 14 together, preferably by means of wire hoops or bands 25.

The second section B of the separator comprises similar staves 14^a but pockets 17^a therein are larger and are adapted to receive 110 the kernels of wheat delivered thereto by

the spiral, the webs of this section forming a continuation of the webs 15 and providing a continuous passage through the rotating member. The staves of this section B are held together by hoops 25^a similar to those already described.

A pan 26 is supported upon a bracket 21^a that is mounted in substantially the same manner as the bracket 21, the pan being positioned near the up side of the rotating member B and the wheat kernels entering the pockets 17^a will be elevated thereby and discharged by gravity into the pan 26 while the oat kernels and refuse foreign material will pass along through the spiral, being too large to enter the pockets, and will finally be discharged into the pan 27 at the end of the machine.

It will be understood that the pans for receiving the separated material are mounted to be readily removable and can be easily taken out of the machine at any time to be emptied or for any other purpose.

For the purpose of centering the staves or bars of the members A and B, I prefer to provide lugs 28 and 29 thereon arranged in pairs as indicated in Figure 1, the lugs of one stave or bar overlapping the abutting edges of the adjacent staves and holding the edges of these staves in alignment in the operation of the machine. It will be understood that this rotating member may be made of any suitable length and the number of separations effected therein may be varied according to the character of the refuse material to be separated from the grain. Generally, however, a machine of the type shown herein will effect the necessary separation, the first section taking out the round seeds and those of such shape that they will enter comparatively small pockets while the second section is adapted for receiving the wheat kernels and separating them from the wild oats and the larger refuse material which may be mixed with the grain.

The machine is preferably horizontal so there will be no tendency of the round seeds to roll down the spiral following the web though without entering the pockets to be separated from the rest of the material. By mounting the rotary member in a horizontal position, any tendency of the round seeds to roll to the discharge end will be prevented and the body of grain and seeds deposited in the machine will be acted on by the pockets and held in the spiral in position to enter the pockets until the desired separation is effected. The webs of the spirals also compel the material to follow a path in the direction of rotation of the member instead of sliding along the bottom thereof as the material might do if the spiral webs were omitted. In other words, the horizontal arrangement of the rotating member and the spiral web on its inner surface insures such a move-

ment of the material that the round seeds and fine material will be effectually separated in the initial section of the machine and the wheat taken out in the following section.

In using the machine to determine the proper grade of a quantity of grain, the operator will weigh the sample before depositing it in the hopper, and when the material has been passed through the machine, the pans will be removed and the proper grading of the carload of grain can be readily determined by the ratio of the seeds and refuse material in two of the pans to the amount of clean wheat in the third pan. In this way, the user of the machine can very accurately determine the proper grade of a body of grain. It will be understood that a machine of this type can be readily adapted for separating wheat from oats, disregarding the finer material or effecting such separation in another machine. In such case, it will only be necessary to extend the wheat receiving pockets throughout the full length of the rotating member instead of only through a section thereof as shown and described. It is also evident that the pockets for receiving the round seeds and fine material may be extended throughout the length of the member instead of terminating near the middle portion thereof. These, however, are obvious modifications of this separating machine and illustration thereof is unnecessary.

I claim as my invention:

1. A dockage tester comprising a rotating member having an interiorly arranged spiral said member having initial and second sections, the wall of the initial section between said spirals having series of pockets therein adapted to collect round seeds and similar fine material, and means for receiving such seeds discharged by gravity from said pockets during the rotation of said member, a second section of said member having pockets in its walls between said spirals adapted to receive kernels of wheat, and means for collecting such kernels during the rotation of said member, and a shaft rotatably supporting said rotating member and connected to said member only medially thereof.

2. A machine of the class described comprising a rotating member horizontally arranged and having means for delivering therein the grain and material to be separated therefrom, said member having groups of pockets in its walls, the initial group receiving the seeds and fine material from the grain, a subsequent group being adapted to collect the wheat kernels, pans also horizontally arranged within said member upon the upwardly moving side thereof in position to collect the seeds and wheat kernels discharged by gravity from said pockets

as said member revolves said pans being vertically adjustable, and means for directing the coarse material too large to enter said pockets through said revolving member to 5 the discharge end thereof.

3. A machine of the class described comprising a sectional revolving member, rows of sections placed end to end, each section comprising a plurality of staves or bars 10 and means for securing them together to form a hollow member polygonal in cross section, the initial section having pockets in its walls adapted to collect the round seeds and fine material, the adjacent section having 15 pockets adapted to receive kernels of wheat, said staves or bars having transverse webs thereon forming when assembled a continuous spiral web from one end of said member to the other, said webs compelling 20 the material delivered to said member to follow a rotary path therein, and be raised in said pockets on the upwardly moving side of said member, and means for receiving the seeds and fine material discharged by 25 gravity from the first group of pockets and the wheat kernels correspondingly discharged from the pockets of the adjacent group.

4. A machine of the class described, comprising a sectional drum, comprising rows of sections secured end to end, each section comprising a plurality of staves and means for securing the staves together, the initial section having pockets of one size adapted 25 to collect seeds and the adjacent section having pockets adapted to collect kernels of wheat, said staves having transverse webs forming, when assembled, a continuous spiral web extending from one end to the 50 other of said member.

5. In a device of the class described, a drive shaft, a drum connected only at its mid-portion with said shaft and having a spiral rib interiorly, pockets between the 55 whorls of the rib, supports extending within the drum lengthwise, from opposite ends, and receptacles arranged upon the supports to receive seeds discharged from the upwardly travelling pockets.

5. In a device of the class described a drive shaft, a drum connected only at its mid-portion with said shaft, and having a spiral rib interiorly, pockets in the inner surface of the drum between the whorls of the rib, the size of the pockets at the receiving end of the drum being smaller than at the discharge end, and receptacles independently mounted and removably arranged within the drum at one side of its axis of 60 rotation, to receive the seeds discharged from the pockets as they travel upwardly, said boxes extending inwardly from opposite ends of the drum substantially to the middle thereof.

65 7. A hollow open end drum having

pockets in its interior surface, a drive shaft connected interiorly and substantially medially of the drum, and acting as the sole support of the drum, and adapted to rotate the drum, independently supported boxes 70 extending inwardly within the drum from opposite ends, each box being substantially one-half the length of the drum, and being arranged to receive material discharged from the pockets as they travel upwardly. 75

8. A dockage tester comprising a rotatable drum having an internally arranged spiral rib, one portion of the wall between the whorls of the rib having a series of pockets adapted to collect seeds, and another portion of the wall having pockets to collect kernels of wheat, open top receptacles, one for each series of pockets arranged lengthwise within the drum, each having an outer wall adjacent the upwardly moving side of the 85 drum, each receptacle extending inwardly from one end of the drum substantially to the middle thereof.

9. In a device of the class described a shaft, a drum connected only at its mid-portion with the shaft and having series of pockets each of different size, in its inner surface, supports having shelf-like extensions within the drum receptacles removably arranged upon the extensions lengthwise 90 of the drum to receive seeds discharged from the pockets as they travel upwardly, said extensions being vertically adjustable.

10. A dockage tester comprising a rotatable drum having an internally arranged spiral rib, one portion of the wall between the whorls of the rib having a series of pockets adapted to collect seeds, and another portion of the wall having pockets to collect kernels of wheat, open top seed-receiving receptacles one for each series of pockets arranged within the drum, at one side of its axis of rotation, adjacent the upwardly moving side of the drum, with the open top at a level above the axis of rotation, each receptacle extending inwardly from one end of the drum substantially to the middle thereof, and each receptacle being removable. 110

11. A dockage tester comprising, a cylinder mounted for rotation about a horizontal axis, and having a spiral rib upon its inner wall arranged to retain and feed the grain, the inner surface of the drum wall between the whorls of the rib having pockets 115 in groups of different size, and receptacles positioned within the drum to respectively receive and retain the seeds delivered by gravity from the different sized pockets.

12. A dockage tester comprising, a cylinder mounted for rotation about a horizontal axis, and having a spiral rib upon its inner wall arranged to retain and feed the grain, the inner surface of the drum wall between the whorls of the rib having pockets in 120

groups of different size and receptacles positioned within the drum to respectively receive and retain the seeds delivered by gravity from the different sized pockets, the receiving sides of said receptacles being parallel with the axis of the drum.

13. A dockage tester comprising, a cylinder mounted for rotation about a horizontal axis, and having a spiral rib upon its inner wall arranged to retain and feed the grain, the inner surface of the drum wall between the whorls of the rib having pockets

in groups of different size and receptacles positioned within the drum to respectively receive and retain the seeds delivered by gravity from the different sized pockets, the receiving sides of said receptacles being parallel with the axis of the drum, said receptacles extending inwardly from opposite sides substantially to the longitudinal middle of the drum.

In witness whereof, I have hereunto set my hand this 3rd day of August, 1925.

ANDREW V. CLELAND.
